UNITED STATES PATENT OFFICE.

DEXTER EDGE, OF PITTSBURGH, PENNSYLVANIA.

LUBRICATING DEVICE.

Application filed February 10, 1922. Serial No. 535,486.

To all whom it may concern:

Be it known that I, DEXTER EDGE, a citizen of the United States, and resident of Pittsburgh, in the county of Allegheny and State of Pennsylvania, have invented certain new and useful Improvements in Lubricating Devices, of which the following is a specification.

This invention relates to lubricating devices, and more particularly to lubricating devices adapted to supply oil to steam in a steam main before it enters a steam engine or like device so that it will be carried to all the moving parts thereof.

One object of this invention is to construct a device of the class described that will provide for a more economical and thorough lubrication of the mechanism with which it is used than devices heretofore used.

Another object is to provide a device that will maintain a constant head of oil so as to furnish a constant supply to the steam regardless of the irregular flow to said device.

A further object is to provide means for forcing the steam to flow from the main through the oil chamber and for forming an area of high velocity in the main where the oil is delivered and atomized.

A still further object is to provide a device having the novel design, construction, and combination of parts hereinafter described, and illustrated in the accompanying drawings, in which—

Figure 1 is a side elevation of the lubricating device of this invention applied to a vertical steam main shown in section.

Figure 2 is a fragmentary top plan of the nozzle.

Figure 3 is a similar elevation of the nozzle.

Figure 4 is a fragmentary sectional elevation through the steam supply pipe leading to the reservoir and pre-heating chamber showing the reducing disk therein.

Referring more particularly to the drawings, the numeral 2 designates the steam main which is composed of standard pipe sections having the usual flanges 3 and joined by the usual collars 4. A disk 5 having an orifice or aperture 6 of considerably less diameter than the inside diameter of the steam main is inserted between the pipe sections and forms a restriction adapted to form a Venturi tube effect. That is, it forms an area of high pressure above the disk, and an area

of higher velocity and lower pressure below the disk.

It will, of course, be understood that applicant does not wish to be limited to the specific main construction described above, since various means may be employed to obtain a Venturi tube effect.

A substantially inverted T-shaped combined oil reservoir and pre-heating chamber 8 is mounted alongside the main 2, and a small diameter pipe 9 leads from a point above the disk 5 in the main into the top of the chamber 8 to supply steam to said chamber for pre-heating the oil and to supply pressure to force the oil from the chamber.

The pipe 9 is divided intermediate its ends, and a standard union fitting 10 is used to join the pipe where divided. A thin metal disk or washer 11 having a hole 12 of less diameter than the internal diameter of the pipe 9 is inserted in the union to restrict the flow of the steam through the pipe.

An oil supply pipe 13 enters the rear end of the chamber 8 at approximately its center. The pipe 13 is adapted to have its other end connected to a source of oil supply, (not shown) such as a force feed or sight feed apparatus of standard design, which will pump the oil up into the chamber 8.

An outlet pipe 14 leads out of the other end of the chamber 8 into the main 2 at a point below the disk 5 where the steam flow is contracted, and at a higher velocity than the flow above the disk but at a lower pressure due to it being in the act of expanding.

A nozzle tube 15 is connected to the pipe 14 and extends into the steam flow path to deliver the pre-heated oil to the steam. The nozzle tube 15 is of standard design and has its upper face cut away at its forward end as at 16 and its end bent slightly upward as at 17 to form an upwardly opening, slightly dished delivery portion.

The conduits or pipes 9, 13, and 14 have valve members 19, 20, and 21, respectively, mounted in their length to control the flow of fluid therethrough.

In operation, oil is forced into the combined oil reservoir and pre-heating chamber 8 through the pipe 13, and steam flows through the pipe 9 into the chamber 8 to pre-heat the oil and force it out through the pipe 14 and nozzle tube 15.

Due to the relatively large volume or head of oil contained in the chamber 8 compared with the size of the pipes or conduits, the pulsations or irregular flow of oil is smoothed out or absorbed, and the oil flows into the atomizing nozzle 15 in a steady flow irrespective of the flow of oil into the chamber 8.

The nozzle 15 extends into the center of the steam flow path where the oil is atomized and mixed with the steam. In the present embodiment of the invention, the steam line is restricted above the nozzle 15 by the disk 5 and, therefore, the steam striking the nozzle is flowing at a higher velocity than the steam before the disk, and so better atomizes the oil.

The restriction in the steam main 2 caused by the disk 5 also serves to cause the steam to circulate through the chamber 8, since the steam above the disk will be at a higher pressure than the steam below the disk, at which point it is expanding to again fill the large diameter main.

While I have shown and described but one embodiment of my invention, it will be understood that I do not wish to be limited thereto, since various modifications in design, construction, and combination of parts may readily be made by those skilled in the art, without departing from the scope of the appended claims.

I claim—

1. The combination with a steam main having a restricted portion intermediate its ends adapted to form a high pressure area above said portion and a low pressure and high velocity area below said portion, of a forced feed lubricator comprising a combined oil reservoir and pre-heating chamber, a conduit leading from said high pressure area in said main into said chamber, a conduit leading from said chamber into the low pressure and high velocity area of said main, and a conduit leading into said chamber from a source of oil supply.

2. The combination with a steam main having a restricted portion intermediate its ends adapted to form a high pressure area above said portion and a low pressure and high velocity area below said portion, of a forced feed lubricator comprising a combined oil reservoir and pre-heating chamber, a conduit leading from said high pressure area in said main into said chamber, a conduit leading from said chamber into the low

pressure and high velocity area of said main, a conduit leading into said chamber from a source of oil supply, said conduits being so proportioned and arranged as to maintain a relatively large body of oil at all times in said chamber, and means for regulating the flow through all of said conduits.

3. The combination with a steam main having a restricted portion intermediate its ends adapted to form a high pressure area above said portion and a low pressure and high velocity area below said portion, of a forced feed lubricator comprising a combined oil reservoir and pre-heating chamber, a conduit leading from said high pressure area in said main into the top of said chamber, a conduit leading from one end of said chamber into the low pressure and high velocity area of said main, said last named conduit extending into the flow path of the steam passing through said main and terminating in an atomizing nozzle, and a third conduit leading into the other end of said chamber from a suitable source of oil supply.

4. The combination with a steam main having a restricted portion intermediate its ends adapted to form a high pressure area above said portion and a low pressure and high velocity area below said portion, of a forced feed lubricator comprising a combined oil reservoir and pre-heating chamber, a conduit leading from said high pressure area in said main into the top of said chamber, said conduit having a restricted portion intermediate its ends, a conduit leading from one end of said chamber into the low pressure and high velocity area of said main, said last named conduit extending into the center of the flow path of the steam passing through said main and terminating in an atomizing nozzle, a third conduit entering the other end of said chamber and adapted to conduct oil to said chamber, said conduits being so proportioned and arranged as to maintain a relatively large head of oil at all times in said chamber whereby any pulsations caused by the irregular flow of oil are absorbed and a constant flow of oil is supplied to said nozzle, and means for regulating the flow through each of said conduits.

In testimony whereof, I have hereunto set my hand.

DEXTER EDGE.
